UNITED STATES PATENT OFFICE.

JACOB RUPPERT, OF NEW YORK, N. Y.

DESIGN FOR A JAR OR BOTTLE.

SPECIFICATION forming part of Design No. 26,790, dated March 23, 1897.

Application filed May 7, 1896. Serial No. 590,622. Term of patent 14 years.

To all whom it may concern:

Be it known that I, JACOB RUPPERT, a citizen of the United States, and a resident of the city, county, and State of New York, have 5 invented a new and original Design for Jars or Bottles, of which the following is a specification.

Figure 1 is a side elevation, and Fig. 2 a sectional view, of a jar or bottle, showing my 10 design.

The leading feature of my design consists in a cylindrical jar or bottle having a flat bottom and flat top surface, the top having a flange surrounding an opening formed therein, the cylindrical portion having a circular 15 projection at one side near the bottom.

A second leading feature consists in a top

for jars or bottles having an approximately rounded upper surface and an approximately flat bottom.

A designates a jar or bottle, and B the top.

a designates the projection at the side and having an opening in and leading through said projection, and b an opening in the top.

What I claim is—

The design for a jar or bottle substantially as herein shown.

In testimony that I claim the foregoing as my design I have signed my name, in presence of two witnesses, this 20th day of April, 1896.

JACOB RUPPERT.

Witnesses:

JOHN G. GILLIG,
FRANK RUPPERT.
